UNITED STATES PATENT OFFICE

WILLIAM C. HUEBNER, OF CHICAGO, ILLINOIS, ASSIGNOR TO HUEBNER-BLEISTEIN PATENTS COMPANY, OF BUFFALO, NEW YORK, A CORPORATION OF NEW YORK

NEGATIVE HOLDER FOR PHOTOGRAPHIC PRINTING MACHINES

Application filed July 27, 1928, Serial No. 295,683. Renewed January 6, 1932.

This invention relates to improvements in negative holders for photographic printing machines.

In the art of making press plates photographically on machines commonly called photo-composers or photographic printing machines, it is the general practice to fasten the negative to a holder or frame which is then attached to a movable carriage of the machine proper. In making the photographic impressions, great pressure is required between the negative and the sensitized or press plate in order to obtain accurate prints and heretofore this pressure has been obtained either by mechanical pressure-applying means or by vacuum, that is, by exhausting the air from between the negative and press plate.

In those machines employing the vacuum system for obtaining pressure, considerable difficulty has heretofore been experienced in providing a complete air sealing means between the several parts necessary to obtain the vacuum between the negative and press plate. The most common form of negative used is, of course, the glass negative plate and so far as I am aware, no means have heretofore been provided by which a vacuum seal could be obtained where a flexible film negative is employed, which flexible films are now coming into use.

One object of my invention is to provide an improved negative holder of the type above referred to which is adapted for either glass or flexible film negatives and wherein a complete air seal is obtainable between the several parts constituting the negative-carrying structure on the one hand and the press plate on the other hand, whereby to obtain the intimate pressure contact between the negative and press plate during exposure.

Another object of my invention is to provide a negative holder of the character indicated wherein the air sealing means are so mounted and disposed on the negative-carrying frames or holders that, when assembled, there is no danger of any of the parts becoming loose or disengaged, to the end that such negative holders may be employed in either horizontal, vertical, or other

position on the machine, thereby permitting adjustments of the negative holder from operative to inoperative position and facilitating the operation and minimizing labor.

Another object of my invention is to provide negative holding means which comprise, essentially, a main holder and a negative holder proper such that the relative levels of said two holders may be varied to compensate for negatives of different thicknesses in combination with air sealing means between the two holders, which will automatically maintain the seal in any relative adjusted levels of the two holders.

Another object of my invention is to provide a negative holder and means associated therewith so arranged as to eliminate or minimize the possibility of the press plate being drawn into any gaps when the vacuum is on to thereby preserve the flat surface contour of the press plate during exposure and prevent distortion of the images printed thereon.

Other objects of the invention will more clearly appear from the description and claims hereinafter following.

In the drawings forming a part of this specification, Figure 1 is a plan view of an improved negative holder embodying my improvements, part of the glass negative being broken away to illustrate certain underlying features. Figure 2 is a broken vertical sectional view corresponding substantially to the line 2-2 of Figure 1, Figure 2 being on an enlarged scale. Figure 3 is a similar vertical sectional view broken away and corresponding substantially to the line 3-3 of Figure 1. Figure 4 is a broken view similar to Figure 2, illustrating the holder as used with a glass negative of lesser thickness than the one illustrated in Figure 2. Figure 5 is a plan view of the negative holder proper, detached. Figure 6 is a transverse sectional view of the holder proper shown in Figure 5 and corresponding to the line 6-6 thereof, parts being broken away to accommodate the figure on the sheet. Figure 7 is a plan view of the guide or gap frame detached. Figure 8 is an end view of the frame shown in Figure 7. Figure 9 is a view

similar to Figure 1, showing the improved holder as adapted for the holding of a flexible film negative. Figure 10 is a sectional view of the construction illustrated in Figure 9 and corresponding to the line 10—10 thereof and on a larger scale. Figure 11 is a detail plan view of the auxiliary frame utilized in holding a flexible film negative and illustrating more particularly one of the 10 clamping and stretching jaws. Figure 12 is a view similar to Figure 1, illustrating a somewhat different embodiment of the invention. And Figure 13 is an enlarged sectional view of the holder shown in Figure 12, corresponding to the line 13—13 thereof.

Referring first to the construction in Figures 1 to 8, inclusive, the improved negative holder comprises, broadly, a main or outer holder or frame A; a negative holder proper 20 or negative frame proper B; and a guide or gap frame C.

The main holder A, as shown, is of rectangular form and consists of a main heavy plate 20 having a rectangular central opening 21 to permit transmission of the light rays therethrough. Around all edges of the plate 20 is provided a sealing arrangement which preferably consists of a strip 22 of sponge rubber held in place by a channel-like arrangement consisting of a bottom plate 23 and side plates 24—24, as shown in Figure 2. The rubber strip will be compressed along its bottom half by the plates 24 when the strip is secured in place so that the strip has, normally, a widened top section as shown, and which is adapted to yield and spread slightly when the holder is applied against the usual press plate. The main holder A is adapted to be mounted directly 40 on the photographic printing machine in a definite predetermined position and location, for which any suitable means may be provided, the one which is illustrated comprising two sets of dowel holes 25—25 and 45 26—26, the former being on one edge and the latter along an edge at right angles thereto, whereby the holder may be turned through an angle of 90° with reference to the carriage or other part of the photographic printing machine, to which it is attached.

The negative holder proper B is also of rectangular outline, since glass negatives generally come in this shape. Said holder 50 B preferably comprises a rigid plate of steel or other suitable material of rectangular cross section, thus providing a flat bottom surface 27, a flat top surface 28 and a vertical flat surface 29 defining the usual rectangular opening therein to permit the passage of the light rays.

In order to properly secure the glass negative D on the holder proper B, the latter is provided with a plurality of adjustable 60 clamps around its periphery, there being six

shown, two each on the long sides and one each on the narrower sides of the frame. Each of said clamps preferably comprises a block 30 from which are extended inwardly two spaced guide pins 31 which work in corresponding holes in the plate and hence maintain the block 30 parallel with the corresponding side of the holder B. Secured to the top of each block 30 is a clamp plate proper 32, preferably having a beveled inner edge 33 adapting it to engage the corresponding beveled edge of the glass negative D (which are customarily so finished). It will be noted from inspection of Figures 2 and 6 that the clamp plates proper 32 are of lesser thickness than the glass negatives so as to positively insure the printing surface of the negative being above the clamps and hence avoiding any possibility of marring the sensitized press plate during exposure. 85 Each clamp is adjusted inwardly and outwardly by a headed screw 34 threaded into the holder plate so that the clamping jaws will be moved inwardly and outwardly, as is clear from the drawings.

Preferably, the holder proper B is recessed as indicated at 35—35 opposite each clamp so as to reduce the over-all dimensions of the holder, as will be understood.

In order to positively insure an air seal 90 between the negative and the holder proper B when the negative is in place, the holder B is supplied with a thin layer 36 of rubber or suitable material on its upper flat surface 28, and it will be obvious that, as the beveled edge clamps secure the negative in place, there is a slight squeezing of the rubber layer 36. In order that the negative holder proper B may be placed and retained in predetermined position and location on the main 1 holder A, the holder B is preferably provided with dowel hole bushings 37 on opposite sides thereof, with which cooperate corresponding dowels on the main holder A.

To hold the holder proper B firmly assembled with the main holder A after the two have been assembled and also to provide for adjustment of the relative levels of the two holders, I employ the following means, best illustrated in Figure 2. At each corner of the main frame A, is a level-adjusting screw 38 having a suitable knurled head 39 by which the spacing between the two holders may be adjusted, as will be obvious. When the proper level of the holder B with reference to the holder A has been obtained, the parts are then locked by four other screws 40, one at each corner, which screws 40 pass freely through the plate 20 of the main holder and have threaded engagement with the holder B. Each screw 40 is also preferably provided with a knurled head 41 to facilitate adjustment thereof. By comparing Figures 2 and 4, it will be noted that the holder B in the latter figure is elevated an appreciable

distance, as compared with its location in Figure 2, in order to bring the level of the thinner glass negative E to the desired point for making pressure contact with the press plate. Incidentally, in Figure 4, it will be noted that the negative E has a square edge and that the clamping plate proper 32 is reversed to meet this condition.

In order to provide a seal between the two holders A and B in any relative adjusted level of the holder B, the following arrangement is preferably employed. Around all four of the inner vertical surfaces 29 of the holder B is applied a flexible flap 42 which may be of rubberized cloth and of sufficient width so that it will always overlap the vertical edge 21 of the main plate 20 in any adjusted position of the holder B. Backing the flap 42 is a strip 43 preferably of sponge rubber and approximately of coextensive width, the rubber also extending around all four inner edges, as will be understood. The flap 42 and rubber strip 43 are secured to the holder B preferably by relatively narrow metal plates 44 and screws 45. In actual practice, when the air is drawn out of the negative holder, as hereinafter explained, the flap 42 will be drawn against the main plate 20 which action is, of course, augmented by the rubber backing strip 43 and hence a slidably adjustable seal is always maintained between the holder B and the main holder A, under all operating conditions.

Due to the fact that there is always necessarily a considerable gap between the edges of the negative and the sealing strip 22 of the main holder A, it is essential to bridge this gap so far as possible, in order that the press plate, when the vacuum is on, will not be drawn in or buckled, and hence destroy register and cause imperfect prints. For this purpose, I employ the level guide or gap frame C, shown in detail in Figures 7 and 8 and in section in Figure 3. Preferably, this frame, which is detachable and removable from the main frame A, is composed of a rectangular frame of wood 46 of suitable height and to the upper surface of which is applied a metal plate 47, wood being employed in order to provide a slight amount of resiliency should there be any variation in the levels of the gap frame and the negative. The gap frame is suitably recessed as indicated at 48-48 to accommodate the clamps and operating means therefor, as clearly shown in the drawings. To hold the gap frame in proper position and prevent its accidental disengagement, I employ at diagonally disposed corners thereof, spring dowel pins 49 secured to the main frame A and adapted to enter corresponding dowel openings 50 in the wood section of the gap frame C.

When the assembled holder is on the photographic printing machine, it will be connected with a vacuum pump, preferably through

either one of the vacuum heads 51-51, two being illustrated, when on a narrow side, it being understood that when one head 51 is in use, the other will be shut off by any suitable valve arrangement.

In carrying out my invention, the level of the surface of the gap frame will be slightly below the normal level of the rubber sealing strip 22 when the latter is free from pressure. The negative D, carried by the holder B, will be adjusted so as to bring the printing surface thereof flush with the surface of the gap frame. When the negative holder assembly is placed in contact with the press plate and the vacuum turned on, it is evident that air will be exhausted from between the press plate and negative holder assembly, thus inducing compression of the rubber sealing strip 22, until the printing surface of the negative is in intimate contact with the sensitized surface of the press plate, whereupon the exposure may be made. The air seal will be maintained between the press plate and the holder assembly by the rubber strip 22. Between the negative and the holder B, the seal will be maintained by the rubber strip 36 and between the holders B and A by the flap 42 and rubber strip 43.

Referring next to the construction illustrated in Figures 9, 10 and 11, the arrangement of main holder A and negative holder proper B and the sealing means associated therewith, is the same. In order to permit the use of flexible film negatives such as shown at 52, I employ an auxiliary holder F. The latter comprises an open rectangular frame preferably built up by employing an upper relatively wide plate 53, a similar lower plate 54 and a vertical edge plate 55. This frame F is secured to the holder proper B by the same clamps previously described for holding glass negatives, one of the clamping plates proper 32 being shown in Figure 10 and similarly, a seal is provided between said auxiliary frame F and the frame B by the same rubber strip 36. When employing the auxiliary holder F, the holder B will be disposed in its lowermost position with reference to the main holder A, as shown in Figure 10, and the seal between the two holders B and A is obtained by the same flap arrangement 42 and rubber strip 43.

At relatively closely spaced intervals around the outer edges of the auxiliary frame F, are provided combined clamping and stretching jaws, each of which includes a block 56 slidably mounted within the channel frame heretofore described and a clamping jaw proper 57. The jaw 57 and block 56 have cooperable wedge-shaped surfaces 58 adapted to engage and secure the edge of the film therebetween, this result being obtained by two clamp screws 59-59. Preferably, coil springs 60-60 are interposed between the jaw 57 and block 56, in order to

70

75

80

110

115

120

125

130

induce separation thereof when the clamp screws 59 are loosened. To effect stretch of the flexible film and to maintain the same taut, the jaw assembly is adjusted with reference to the auxiliary frame, by means of a headed adjusting screw 61. By employing a plurality of clamping and stretching jaws, it is evident that the degree of tension at various points on the film may be regulated to produce the necessary register of the image thereon, all as more clearly set forth in my pending application Serial No. 729,277, filed on or about July 31, 1924.

Very frequently flexible film negatives of paper will be employed, particularly in large work such as poster work, which paper film may not be entirely leakproof. To overcome any possibility of leakage through the film, I employ a film 90 entirely bridging the light opening and the edges of which are secured to the inner edges defining the opening of the film frame F by plates 91. Said film 90 will preferably be of celluloid, of sufficient thickness to provide a suitable backing for the negative film proper but thin enough to prevent interference with the transmission of light rays. If desired, a rubber strip 92 may be placed on the top surface of the film frame F beneath the negative film proper so as to further insure against leakage when the vacuum is on.

Referring to the modification shown in Figures 12 and 13, the only difference there indicated is with reference to the main holder, which, in this instance, is provided with its own gap or bridging means. As shown, the main holder has a main plate 120, an outer vertically extending plate 124 and an inner vertically extending plate 146. Secured to the upper surfaces of the plates 124 and 146 is a horizontal plate 70 which is suitably notched as indicated at 71-71 to accommodate the negative clamping jaws, said plate 70 also being provided with a series of openings or perforations 72-72 on all four sides, which communicate with a rectangular channel or chamber 73 formed by the plates 20, 124, 146 and 70. A portion of the upper surface of the plates 70 extending from a point outside of the perforations 72 completely to the inner edge of the plate, is deeply knurled, as indicated at 75, thereby providing a large number of air ducts, as best indicated at 173 in Figure 13, to more readily permit exhaustion of the air from beneath the negative and negative holder proper B and to positively insure exhaustion of the air throughout the entire area of contact with the press plate and thus prevent any air traps. The seal between the main holder in this construction is obtained by a flap of rubberized cloth, or the like 74, which is backed by a strip of rubber sponge or the like 76, the flap and sponge being secured to the plate 124 by a narrow plate 77, as clearly shown in Figure

13. In this construction only one vacuum head 78 is indicated, which is adapted to be connected with a suitable vacuum pump, as will be understood.

With the construction just described, it is evident that separate gaps or bridging frames are rendered unnecessary and to accommodate different size negatives, a series of corresponding different size main holders will be employed. Preferably, these main holders will be made principally of aluminum to lessen the weight and to facilitate handling.

I claim:

1. In a negative holder for photographic printing machines, the combination with a main holder having air sealing means adapted to engage a print-receiving surface; of a negative holder proper; means for retaining the two holders in predetermined assembled relation; and air sealing means directly effective between said two holders.

2. In a negative holder for photographic printing machines, the combination with a main holder having air sealing means adapted to engage a print-receiving surface; of a negative holder proper; adjustable means operative between the two holders for retaining them in relative predetermined position and location and at different levels to compensate for variable thickness of negatives; and air sealing means directly effective between the two holders.

3. In a negative holder for photographic printing machines, the combination with a main holder having means adapted to provide an air seal with a print-receiving surface; of a negative holder proper; means providing an air seal between said holder proper and a negative when secured thereto; and means carried by one of said holders operable with the other holder to provide an air seal between the two holders.

4. In a negative holder for photographic printing machines, the combination with a main holder having air sealing means co-operable with a print-receiving surface; of a negative holder proper; adjustable means for retaining the negative holder proper at different levels with respect to the main holder; and air sealing means carried by one of the holders and adjustably engaging the other of said holders.

5. In a negative holder for photographic printing machines, the combination with a main vacuum frame holder having air sealing means co-operable with an opposed print-receiving surface; a negative holder proper disposed within the confines of and of lesser area than said vacuum frame holder whereby gaps are left between the negative and said sealing means; and means disposed within said gaps and substantially flush with the negative surface whereby to prevent displacement of the print-receiving surface within said gaps when the vacuum is on.

6. In a negative holder for photographic printing machines, the combination with a main vacuum frame holder having air sealing means cooperable with an opposed print-receiving surface; a negative holder proper disposed within the confines of and of lesser area than said vacuum frame holder whereby gaps are left between the negative and said sealing means; and a removable frame disposed within said gaps and having its upper surface substantially flush with the negative surface whereby to prevent displacement of the print-receiving surface within said gaps when the vacuum is on. 70
- 10 7. In a negative holder for photographic printing machines, the combination with a main vacuum frame holder having air sealing means cooperable with an opposed print-receiving surface; a negative holder proper disposed within the confines of and of lesser area than said vacuum frame holder whereby gaps are left between the negative and said sealing means; a detachable gap-bridging frame surrounding the negative holder proper; and means for retaining said gap-bridging frame assembled with the main holder. 80
- 15 8. In a negative holder for photographic printing machines, the combination with a main holder having a central opening and provided with means adapted to form an air seal with an opposed print-receiving surface; a negative holder having a central opening in register with said first named central opening; means for adjusting the level of the negative holder with reference to the main holder; and means providing an air seal between said two holders. 85
- 20 9. In a negative holder for photographic printing machines, the combination with a main holder having a central opening and provided with means adapted to form an air seal with an opposed print-receiving surface; a negative holder having a central opening in register with said first named central opening; means for adjusting the level of the negative holder with reference to the main holder; means for accurately predetermining the position and location of the negative holder with reference to the main holder; and adjustable means providing an air seal between the two holders at any level of the negative holder with reference to the main holder. 90
- 25 10. In a negative holder for photographic printing machines, the combination with a main holder; of a negative holder; and means providing an air seal between said holders, said means including a flexible flap bridging the gap between the two holders and a resilient backing for said flap. 95
- 30 11. In a negative holder for photographic printing machines, the combination with a main holder having a central opening defined by vertical edges of the main holder; of a negative holder having a central opening defined by vertical edges thereof and of the same size and contour as the opening in the main holder; means for adjusting the level of the negative holder with reference to the main holder; and means for sealing the joint between the two holders along their vertical edges defining the openings, said means including a flexible flap secured to one of said holders and extending loosely over the joints. 100
- 35 12. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery thereof; adjustable means for varying the level of the negative holder proper with reference to the main holder; air sealing means between the two holders effective in any relative adjusted position of the negative holder; and cooperating means between the two holders for positioning and locating the negative holder proper with reference to the main holder in a predetermined position 105
- 40 13. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery thereof; adjustable means for varying the level of the negative holder proper with reference to the main holder; air sealing means between the two holders effective in any relative adjusted position of the negative holder; cooperating means between the two holders for positioning and locating the negative holder proper with reference to the main holder in a predetermined position 110
- 45 14. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery, 115
- 50 15. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery, 120
- 55 16. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery, 125
- 60 17. In a negative holder for photographic printing machines, the combination with a rectangular main holder having a central rectangular opening, a flat bottom plate and air sealing means extending around the periphery on one side thereof; of a negative holder proper of rectangular form and having a central rectangular opening in register with the opening of the main holder, said negative holder proper having a plurality of adjustable clamping jaws around the periphery, 130

thereof adjustable means for varying the level of the negative holder proper with reference to the main holder; air sealing means between the two holders effective in any relative adjusted position of the negative holder; cooperating means between the two holders for positioning and locating the negative holder proper with reference to the main holder in a predetermined position and location; and a removable gap frame supported on the main holder and disposed around the periphery of the negative holder proper, said gap frame being provided with recesses to accommodate the clamping jaws of the negative holder proper.

15 In witness that I claim the foregoing I have hereunto subscribed my name this 18th day of July, 1928.

WILLIAM C. HUEBNER.
